UNITED STATES PATENT OFFICE

2,508,737

VENETIAN BLIND-DRAPE-END FIXTURE

Jim Zeto, Tampa, Fla.

Application July 1, 1949, Serial No. 102,622

5 Claims. (Cl. 248—264)

1

This invention relates to a bracket or fixture of novel construction adapted to be secured to a window casing or wall adjacent the top thereof.

The primary object of this invention is to provide a bracket or fixture including means for simultaneously supporting and retaining a Venetian blind head rail, drape rods, and a valance.

Another object of this invention is to provide a bracket or fixture which is relatively simple in design and construction, cheap to manufacture, extremely easy to secure or attach to a window casing or wall, and attractive in appearance.

A further object of this invention is to provide a bracket or fixture which will make it unnecessary to provide separate brackets for supporting a Venetian blind head rail, drape rods and a valance as is conventionally done at the present time.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of a pair of brackets of one modification of the present invention shown secured to a window casing and supporting the Venetian blind head rail, the drape rods, and the valance;

Figure 2 is a sectional view taken substantially on the plane of section line 2—2 of Figure 1;

Figure 3 is a perspective view of one of the brackets shown in Figures 1 and 2 and illustrating the manner in which it is attached to the window casing;

Figure 4 is a perspective view of another modification of the bracket of the instant invention shown secured to a window casing and supporting the Venetian blind head rail, the drape rods, and the valance;

Figure 5 is a perspective view of the bracket itself, and

Figure 6 is a sectional view taken substantially in the plane of section line 6—6 of Figure 4.

Specific reference is now made to the drawings. In the several views in the accompanying drawings and in the following specification reference characters indicate corresponding elements throughout.

In the modification shown in Figures 1 to 3, there is indicated generally at 10 a wall to which is secured a window casing 12 having an inner wall section 14 and an outer wall section 16. The bracket or fixture is generally indicated at 18 and

2

as will be readily understood two such brackets will be required for each window casing to properly support the head rail, the drape rods, and the valance.

5 In the description which follows hereinafter, only one fixture or bracket 18 will be described, it being understood that the other fixture or bracket is identical in construction and design to the one described. The bracket 18 consists of an L-shaped plate or member 20 having an inner leg portion 22, an outer leg portion 24 and a web portion 26 connecting the leg portions. The leg portion 22 is positioned against the outer wall section 16 of the casing 12 and is provided with a laterally extending plate 28 positioned against the inner wall section 14 of the casing. The plate 28 is apertured to receive a fastening means, such as screws 30, for securing the plate 28 to the casing wall 14.

10 Secured as by welding or riveting 32 to the plate 28 is an L-shaped or angle bracket 34 which is apertured as at 36 to receive a fastening pin 38 attaching the Venetian blind head rail 40 to the angle bracket 34.

15 25 An L-shaped bracket 42 is provided which has a depending extension 44 which is secured as by welding or riveting 46 to the web portion 26 of the fixture 18. The vertically extending leg portion 48 of the L-shaped bracket 42 is provided with spaced slots or notches 50 for removably retaining drape rods 52.

20 30 The outer leg 24 of the fixture 18 is off-set as at 54 to provide an extension 56. Suitably secured to the inner surface of the leg 24 is a vertically extending plate 58 which is provided with a forwardly extending lateral projection 60 at its bottom edge adapted to underlie the bottom edge of the extension 56 and to form therewith a channel 62 for slidably receiving a valance 64.

35 40 In the modification shown in Figures 4 to 6, the bracket is shown at 66 and is similar in general construction to the bracket 18 except that the laterally extending plate 28 is dispensed with so that the bracket is secured directly to the outer wall section 16.

45 50 The bracket 66 is generally U-shaped and has an inner leg portion 68 and an outer leg portion 70 interconnected by a web portion 72. As shown clearly in the drawings, the leg portion 68 is secured to the outer wall 16 by means of screws 74 extending through suitable apertures 76 in the leg portion 68. Welded or riveted as at 78 adjacent the top edge of the leg portion 68 is an L-shaped bracket 80 for receiving the Venetian blind head rail 40 which is secured to the bracket

80 by means of suitable screws 82 depending through suitable apertures 84 in the bottom leg of the bracket 80.

A bracket 86 identical in construction and design to the L-shaped bracket 42 is riveted to the web portion 72 of the bracket 66 and is provided with the spaced slots or notches 88 for receiving and removably retaining the drape rods 52.

The outer leg 70 of the bracket 66 is also off-set as at 90 to provide an extension 92. Suitably secured to the inner surface of the leg 70 is a vertically extending plate 94 which is provided with a forwardly extending lateral projection 96 at its bottom edge adapted to underlie the extension 92 and form therewith a channel 98 for slidably receiving a valance 64.

The fixtures or brackets 18 and 66 may be fabricated of any suitable material but preferably of a rigid metal that may be attractively painted as desired.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A supporting bracket comprising a U-shaped member, a lateral extension carried by one leg of said member and adapted to be secured to a window casing, means carried by said extension for supporting a Venetian blind head rail, means carried by the web portion of said U-shaped member for supporting drape rods, and means carried by the other leg of said U-shaped member for retaining a valance. 40

2. A supporting bracket comprising a U-shaped member, means for securing said member to a window casing, means carried by one leg of said member for supporting a Venetian blind head rail, means carried by the web portion of said U-shaped member for supporting drape rods, and means carried by the other leg of said U-shaped member for removably retaining a valance. 50

3. The combination of claim 2, wherein said first-named means includes fastening pins for securing said one leg to a window casing, and wherein said second-named means includes an angle bracket.

4. A supporting bracket comprising a U-shaped member, means for securing said member to a window casing, means carried by one leg of said member for supporting a Venetian blind head rail, means carried by the web portion of said U-shaped member for supporting drape rods, and means carried by the other leg of said U-shaped member for removably retaining a valance, said first-named means including fastening pins for securing said one leg to a window casing, said third-named means including an L-shaped plate, an extension on one leg of said plate secured to the web portion of said U-shaped member, and spaced notches in the other leg of said L-shaped member adapted to receive drape rods.

5. A supporting bracket comprising a U-shaped member, means for securing said member to a window casing, means carried by one leg of said member for supporting a Venetian blind head rail, means carried by the web portion of said U-shaped member for supporting drape rods, and means carried by the other leg of said U-shaped member for removably retaining a valance, said first-named means including fastening pins for securing said one leg to a window casing, said last-named means including an offset portion carried at the free end of said other leg and a plate secured to said other leg having a lateral extension at the bottom of said plate underlying the bottom edge of said offset portion forming a channel between said plate and said off-set portion for slidably receiving a valance.

JIM ZETO.
